JACQUES HENRI MORISSEAU, OF PARIS, FRANCE.

NOZZLE FOR SPRAYING LIQUIDS WITH ADJUSTABLE SCATTERING EFFECT.

Application filed November 27, 1922. Serial No. 603,685.

To all whom it may concern:

Be it known that I, JACQUES HENRI MORISSEAU, 9 Rue de la Roquette, Paris, France, have invented Nozzles for Spraying Liquids 5 with Adjustable Scattering Effect, of which the following is a full, clear, and exact description.

This invention relates to improvements in nozzles of the type which permits varying 10 the volume and the shape of the stream of liquid issuing therefrom.

This invention has for its object to provide a new nozzle allowing the obtaining of a conical spray or jet of finely divided liquid, 15 the angle of which may be varied at will the liquid having to undergo only a small loss of velocity.

The invention is characterized by the combination with the nozzle of a ground cock 20 the plug of which is inclined with reference to the axis of this nozzle. This plug is fixed while the shell or box carrying the nozzle is movable.

When the ports of the plug and of the 25 shell do not correspond, the liquid jet ejected from the plug impinges the internal surface of the nozzle at an angle and has thus imparted thereto an helical or screw motion the pitch of which becomes smaller as the 30 discharge area of the nozzle decreases. This device allows the obtaining of a conical open spray whose angle of divergence can be varied between 0° and 90° by simply turning the plug with reference to the shell or box.

The accompanying drawing shows by way 35 of example two ways of carrying out the invention as applied to watering or fire spray-
ers.

Figure 1 is a longitudinal section of the 40 apparatus.

Figure 2 is a longitudinal section of the apparatus in another position.

Figure 3 is a section through A—A of Figure 1.

Figure 4 is a section through B—B of Figure 2.

Figure 5 is a longitudinal section of a modified form.

As shown in this drawing, the apparatus 50 comprises a conical tube *a* having at one end an internally threaded socket *b* which allows it to be secured as an ordinary sprayer, upon a joint placed at the end of a water-hose.

At the other end, the tube *a* is provided 55 with a conical bearing *c* in the side wall of which the end of the bore of the tube *a* ter-

minates in an opening *d*. This axis of the bearing is inclined relatively to the axis of the tube.

On this bearing *c* can turn a shell or box 60 of a corresponding shape, *e*, maintained in position by a washer *f* and a nut *g* screwed upon a threaded stem which terminates the bearing *c*. In the mass of this shell *e* is formed a conical nozzle *h* the axis of which 65 is inclined with reference to that of the shell. These different parts are combined so that the bore of the nozzle *h* can be brought exactly into alignment with the bore of the tube *a* as shown in Figs. 1 and 3. In this position, the apparatus works as in an ordinary sprayer nozzle.

If the shell is turned according to a certain angle, Figs. 2 and 4, the bore of the nozzle is inclined relative to the bore of the 75 tube *a*, and the opening *a* is partially covered. The result is that the liquid strikes at an angle the internal surface of the nozzle, is deflected and takes accordingly an helical or screw motion. When coming out 80 of the apparatus, the different particles of the liquid have not, as in the usual sprayers, a direction which is parallel with the axis of the jet but move at an inclination relatively to this axis. The whole forms a wide 85 conical jet or spray of finely divided liquid.

If the nozzle is turned to a greater angle, the liquid will strike it more obliquely, the course followed by the liquid is that of a screw with smaller pitch, and the speed of 90 the different particles is more inclined towards the axis. The liquid then issues from the nozzle in the form of an open cone-like spray. On the contrary, when the nozzle is turned to a smaller angle, the angle 95 at the apex of the cone decreases. The only noticeable loss of head which the liquid undergoes in the apparatus is that which is due to the reduced section of passage between the conical tube and the nozzle; any- 100 how, the same is very small and much smaller than the one prevailing in the devices which have been heretofore used.

Finally, the jet or spray can be entirely stopped by turning the shell a sufficient 105 amount, just as with a cock.

Figure 5 shows a modified form in which the nozzle *i* is fixed, as in an ordinary sprayer, upon the body of the sprayer *j*.

This nozzle *i* comprises a cock or tap 110 with shell, the movable plug *k* of which is inclined relatively to the axis of the nozzle

i. The operation is the same as in the previous apparatus.

As it will be understood from the preceding specification, the apparatus forming the subject-matter of the present invention, can produce either a full cylindrical jet or spray, a pulverized conical jet forming an angle at the apex included between 0° and 90° , or can entirely stop the outflow of liquid. In this apparatus, the breaking up or atomization is obtained without any important loss of head.

It is evident that the principle of the invention is applicable to devices other than fire hose nozzles, and it may, for example, be applied to garden and other types of sprinkler nozzles.

The above described arrangements have been given as examples only. The forms, sizes and materials used can of course vary without departing from the principle of the invention.

Claims:—

1. In a nozzle, a member having a taper-
25 ing bore, a valve mounted in said member

and rotatable about an axis, disposed obliquely to said bore and having an opening therein adapted to register with and correspondingly tapered to said bore.

2. In a nozzle, two members, one adapted to rotate within the other, one of said members having a longitudinally tapered bore therein and the other member having a single tapered passage therein, arranged obliquely to the axis thereof and adapted to register and correspond with the taper of the bore of the first mentioned member.

3. In a nozzle, a body member, a valve rotatably mounted in said body member, a nozzle carried by the body member having a tapered bore extending obliquely to the axis of the valve, said valve having an opening therein adapted to register and corresponding in taper to the tapered bore.

The foregoing specification of my "Nozzle for spraying liquids with adjustable scattering effect" signed by me this 14th day of November, 1922.

JACQUES HENRI MORISSEAU.
